Inventor

By his Attorney, John F. Sherlock
Charles H. Wilson.

UNITED STATES PATENT OFFICE.

JOHN F. SHERLOCK, OF NEW YORK, N. Y., ASSIGNOR OF ONE-HALF TO CHARLES L. O'REILLY, OF NEW YORK, N. Y.

TICKET-HOLDER, PAY-ENVELOP, AND THE LIKE.

1,292,967.

Specification of Letters Patent. Patented Jan. 28, 1919.

Application filed February 5, 1917. Serial No. 146,739.

To all whom it may concern:

Be it known that I, JOHN F. SHERLOCK, residing at New York, in the county and State of New York, have invented certain new and useful Improvements in Ticket-Holders, Pay-Envelops, and the like, of which the following is a specification.

This invention relates to an improved holder or envelop, more particularly to an envelop for receiving money, as a pay envelop, or an envelop adapted to accompany goods and to contain the bill, as when goods are sent to a customer C. O. D.

The prime object of the invention is to provide an envelop which can be manufactured at a minimum cost and of such construction that while being in every way as efficient as the device of this character now in use, it can be also utilized to carry printed advertisements, coupons, and other data of interest to the employee receiving a pay envelop, or the purchaser to whom goods have been sold.

The device may also be conveniently used as a ticket holder for theater, transportation or other tickets or coupons.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawing which forms a part of this specification:

Figure 1 is a diagrammatic view from which the holder or envelop is formed.

Fig. 2 is a vertical sectional view taken through the device when the blank has been folded to the commercial form.

Fig. 3 is a view in elevation, of the completed device.

Fig. 4 is a diagrammatic view of a slightly different embodiment of the invention.

Fig. 5 is a vertical sectional view of the embodiment shown in Fig. 4, when the blank has been folded to the commercial form.

Fig. 6 is an elevational view of the embodiment of my invention disclosed in Fig. 4.

Similar reference characters refer to simi-

lar parts throughout the several views of the drawings.

Referring now to the drawings, A represents a blank of the necessary shape to produce the improved envelop or holder. This blank it will be observed comprises the five substantially rectangular parts 1, 2, 3, 4 and 5 respectively. The part 5 is provided with a flap 6, which is a closing flap of the envelop and said part 5 is also provided with the small flaps 7 and 8. The part 2 is provided with the flap 9 which is joined to the part 2 along the line 10, which is preferably weakened for a purpose which will be hereinafter pointed out. The part 4 is cutaway as at 11.

In forming the envelop from the blank A, the flaps 7 and 8 of the part 5 are folded over upon the part 5 and then the part 5 is folded over upon the part 4 upon the line 12. The flaps 7 and 8 are then pasted along the edges 13 and 14 of the part 4, so that an envelop is formed by the parts 4 and 5, having three sides closed and the edges of this envelop which are formed by pasting the flaps 7 and 8 to the part 4, are strengthened by the double thickness of material at these points. It will be noted that it is the rear surface of the flaps 7 and 8 that are pasted to the edges 13 and 14 respectively of the part 4.

When this operation has been accomplished, it will be noted that the flaps 6 can be doubled over the outer end of the part 4 so as to provide a closing member for said envelop. The flap 6, if desired, may be gummed, as at 15, so that the envelop can be completely closed, which is desirable, of course, when the device is used as a pay envelop. The cutaway portion 11 of the part 4 facilitates the insertion of money, or any other object, into the envelop.

The parts 1 and 3 of the blank are then folded over upon the lines 16 and 13, so that said parts are superimposed upon the parts 2, 4, and the back of part 5, which has already been positioned over the part 4, as has already been described.

When this has been done, the next operation is to fold the device along the lines 14 and 17, which completes the operation of forming the holder, leaving the flap 9 to be folded over the device, as shown in Fig. 3.

The embodiment of my invention shown in Fig. 4 is of precisely the same construction as that shown in Fig. 1, except that the cut-away portion 18 is of a different shape than 5 that as shown at 11 in Fig. 1, and the flap corresponding to the flap 6 has been omitted. The device when folded takes the appearance of Fig. 6. It will be noted that this embodiment of the invention is particularly 10 adapted for holding tickets, inasmuch as the cutaway portion 18 enlarges the opening of the envelop. If desired, a flap such as 6 shown in the embodiment of Fig. 1, may be provided to close the open end of this envelop. 15

The flap 9, which is preferably joined to the part 2 by a weakened line, may be utilized as a receipt coupon, as when the device is employed as a container for a bill, that is, 20 when the goods are delivered the recipient can sign the receipt, provided upon this flap, and the carrier can return this to the person from whom the goods were purchased.

Both sides of the parts 1, 2 and 3 may be 25 utilized for the purposes of carrying advertising matter, and the rear surface of the parts 4 and 5 can be similarly used. Thus when the envelop is used as a pay envelop, the employer may print upon any one of 30 these spaces various instructions to his employees, or the name of a savings bank may be printed thereon, calling the attention of the employee to an institution where his savings may be deposited.

When the device is used by concerns selling merchandise various advertisements may be printed upon the blank spaces provided upon the device, thereby bringing the purchaser into intimate contact with the advertisement to which it is desired to direct his attention. 35

While I have described the part 5 as having its edges secured to the part 4 when they lie in superimposed relation to form the envelop, it is obvious that for some purposes 45 it will not be necessary to so fasten them together, because when the device is in such a position a complete pocket is formed without any fastening means whatever being provided between aforesaid parts.

Having thus described my invention what I claim as new and desire to secure by Letters Patent is:

1. A device of the class described, comprising a blank having a part adapted to be folded over on another part of said blank and to be pasted thereto on two of its marginal edges to form a pocket having three sides closed, said part that is folded over being provided with a flap and the part which the first named part is folded upon having a cutaway portion, said blank having other parts of dimensions equal to that of the parts 55 60

providing the envelop adapted to fold upon themselves and one of said parts being provided with a closing flap. 65

2. A device of the class described, comprising a blank formed of four rectangular parts and having a fifth rectangular part joined to one of said parts, said last named 70 part being adapted to be folded over upon one of said last named parts and pasted thereto along two of its marginal edges to form an envelop having three sides closed, and said last named part being provided with a closing flap for said envelop, the other rectangular parts of said blank being 75 so folded upon themselves as to reduce the size of the blank to that of the envelop.

3. A device of the class described, comprising a blank formed of four rectangular parts, one of said parts having a cutaway portion, a fifth rectangular part joined to said last mentioned parts and having a flap, 80 said last two mentioned parts being folded 85 upon each other and joined together along their edges to form an envelop having three sides closed, the remaining parts being folded upon themselves and upon said envelop portion. 90

4. A device of the class described, comprising a blank formed of four rectangular parts, one of said parts having a cutaway portion, a fifth rectangular part joined to said last mentioned part and having a flap, 95 said last two parts being folded upon each other and joined together so as to form an envelop having three sides closed, the remaining rectangular parts being folded upon themselves and upon said envelop, and one of said remaining parts being provided with a flap joined to it by a weakened line. 100

5. A device of the class described, comprising a blank formed of four rectangular parts, and having a fifth laterally disposed 105 rectangular part joined to one of said first mentioned parts, said laterally disposed part being adapted to be folded over the part to which it is attached and cemented thereto along two of its marginal edges to form an 110 envelop having three sides closed, said laterally disposed part being provided with a flap and the part to which it is attached being provided with a cutaway portion, and the remaining rectangular portions being adapted 115 to be folded upon themselves and superimposed upon said envelop portion and one of said remaining parts being provided with a flap which is adapted to extend partially about said envelop portion. 120

In testimony whereof I affix my signature in the presence of two witnesses.

JOHN F. SHERLOCK.
